UNITED STATES PATENT OFFICE.

CONRAD C. BURGDORF, OF HOWELL, INDIANA.

DESIGN FOR A TOILET-CASE.

49,640.

Specification for Design. Patented Sept. 12, 1916.

Application filed July 11, 1916. Serial No. 108,750. Term of patent 7 years.

To all whom it may concern:

Be it known that I, CONRAD C. BURGDORF, a citizen of the United States, residing at Howell, in the county of Vanderburg and State of Indiana, have invented a new, original, and ornamental Design for Toilet-Cases, of which the following is a specification, reference being had to the accompanying drawing, forming part thereof.

The figure is a perspective view of the toilet case, showing my new design.

I claim:

The ornamental design for a toilet case, as shown.

CONRAD C. BURGDORF.

Witnesses:

WILLIAM S. HEURICH,
SEBASTIAN HEURICH.
